UNITED STATES PATENT OFFICE

165,506

ONE-PIECE SUN SUIT

Bernice A. Brenner, Hollywood, Fla.

Application April 13, 1951, Serial No. 14,830

Term of patent 7 years

(Cl. D3—17)

To all whom it may concern:

Be it known that I, Bernice A. Brenner, a citizen of the United States, residing at Hollywood, county of Broward, and State of Florida, have invented a new, original, and ornamental Design for a One-Piece Sun Suit, of which the following is a specification, reference being had to the accompanying drawing, forming a part thereof.

I claim:

The ornamental design for a one-piece sun suit, as shown.

BERNICE A. BRENNER.
